UNITED STATES PATENT OFFICE

FRANK C. HACHENEY, OF VANCOUVER, WASHINGTON

DESIGN FOR A HEADLIGHT

Application filed June 5, 1930. Serial No. 35,906. Term of patent 14 years.

To all whom it may concern:

Be it known that I, FRANK C. HACHENEY, a citizen of the United States, and a resident of the city of Vancouver, county of Clarke, and State of Washington, have invented a new, original, and ornamental Design for a Headlight, of which the following is a specification, reference being had to the accompanying drawings, forming part thereof.

The dominant feature of my invention is the design of the light outlet at the front of the headlight having a metal rim of circular outline and an inner central rectangular opening defining a lens in rectangular outline.

I claim:

The ornamental design for a headlight, as shown and described.

FRANK C. HACHENEY.
